[57] CLAIM

The ornamental design for tire tread, as shown and
described.

DESCRIPTION

FIG. 1 is a front left isometric view of a tire tread showing
my new design, it being understood that the pattern is
repeated uniformly throughout the circumference of the
tread, as shown schematically by solid lines, and that the
opposite side isometric view is identical thereto; and.

FIG. 2 is a plan view of the tire tread portion of FIG. 1
projected onto the page.

The broken line showing of a tire inner bead and sidewall is
for illustrative purposes only and forms no part of the
claimed design.
